Primary Examiner — John M Otte(74) *Attorney, Agent, or Firm* — BCF LLP(57) **CLAIM**

The ornamental design for a display screen or portion thereof with graphical user interface, as shown and described.

DESCRIPTION

FIG. 1 is a front view of a 1st embodiment of a display screen or portion thereof with graphical user interface according to my design;

FIG. 2 is a front view of a 2nd embodiment of a display screen or portion thereof with graphical user interface according to my design;

FIG. 3 is a front view of a 3rd embodiment of a display screen or portion thereof with graphical user interface according to my design;

FIG. 4 is a front view of a 4th embodiment of a display screen or portion thereof with graphical user interface according to my design;

FIG. 5 is a front view of a 5th embodiment of a display screen or portion thereof with graphical user interface according to my design; and,

FIG. 6 is a front view of a 6th embodiment of a display screen or portion thereof with graphical user interface according to my design.

The broken lines showing a display screen and portions of the display screen or portion thereof with graphical user interface form no part of the claimed design.
